Primary Examiner — Holly Baynham*Assistant Examiner* — Rhea Shields*(74) Attorney, Agent, or Firm* — Volpe and Koenig, P.C.**(57) CLAIM**

The ornamental design for a magnetic stirrer, as shown and described.

DESCRIPTION

FIG. 1 is a top, front, right perspective view of a magnetic stirrer in accordance with our design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom view thereof.

In the drawings, the broken lines are for the purpose of illustrating environment only and form no part of the claimed design.
